(57) **CLAIM**

The ornamental design for a saw tooth for radial saw blade, as shown and described.

DESCRIPTION

FIG. 1 is a right side elevation view of a saw tooth, the left side elevation view being a mirror image;

FIG. 2 is a top plan view of the saw tooth illustrated in FIG. 1;

FIG. 3 is a rear elevation view of the saw tooth illustrated in FIG. 1;

FIG. 4 is a front elevation view of the saw tooth illustrated in FIG. 1; and,

FIG. 5 is a right side elevation view of a radial saw blade with the saw tooth illustrated in FIG. 1.
